UNITED STATES PATENT OFFICE.

GEORGE AVERY FRANKLIN, OF AUGUSTA, GEORGIA.

CLOTH-FEED INTERRUPTER FOR AUTOMATIC LOOMS.

Application filed September 21, 1921. Serial No. 502,287.

To all whom it may concern:

Be it known that I, GEORGE A. FRANKLIN, a citizen of the United States, residing at Augusta, in the county of Richmond and 5 State of Georgia, have invented certain new and useful Improvements in Cloth-Feed Interrupters for Automatic Looms, of which the following is a specification, reference being had therein to the accompanying 10 drawing.

This invention relates to cloth feed interrupters, and more particularly to an interrupter used on an automatic loom for arresting the take-up motion so that a filling 15 strip of reinforcing or ornamenting material may be conveniently inserted.

It is one of the essential objects of this invention to provide a simple and efficient device of this character, which may be readily 20 applied to a loom in such manner that the pick wheel pawl is thrown out of engagement with the pick wheel so that the take-up motion is interrupted for a predetermined number of picks, in accordance 25 with the desire of the operator.

Further objects of the invention will appear as the following specific description is read in connection with the accompanying drawing, wherein—

30 The figure shows an elevation of the preferred embodiment of my invention—and while the present structure is more particularly adapted for a standard Northrop loom, I wish it understood that the same 35 principle or broad idea, which is herein involved, may be applied with slight changes to other types of automatic looms, and I do not wish to be, in any sense, restricted by the particular construction shown, or in any 40 other manner except as limited in the subjoined claims.

In order that the invention may be better understood, I have shown several parts of the Northrop loom, 1 indicating the cloth 45 roller stand; 2 the pick wheel which is journaled thereon; 3 the pick wheel pawl which is operated in the usual manner by parts not shown, and 4 and 5 the cam shaft and the filling cam follower respectively.

50 Bolted to the cloth roller stand or otherwise secured thereto is an arm 6 having journaled upon a stub shaft 7, in its outer end, a ratchet wheel 8, which is actuated, as will be hereinafter described, by a pawl 9 pivoted upon the filling cam follower 5. This ratchet wheel is held against retrograde

movement by means of a pawl 10, normally held in engagement with the teeth of the wheel by a spring 11, connected to the arm 6, and to the pawl 10, as shown. The ratchet 60 wheel 8 carries a stud 12 which in practice preferably carries an anti-friction roller, and is adjustable toward and away from the axis of the ratchet wheel for a purpose to be hereinafter described. This stud, at certain 65 periods, wipes over an arm 13 pivotally and adjustably mounted at its opposite end upon the frame of the loom, as shown at 14. The arm is connected to the engaging end of the pawl 3 by a link 15, as shown. 70

In the operation of the device the filling 75 cam follower, which is pivoted to the frame of the loom, as is usual, rises and falls with the rotation of the cam 16 on the shaft 4. As the follower rises the pawl 9 rides idly 80 over the teeth and as the follower is lowered the pawl positively engages the teeth and rotates the wheel 8 a predetermined distance. When the stud 12 engages the arm 13 it depresses the same, carrying with it 85 through the instrumentality of the link 15, the engaging end of the pawl 3 thus withdrawing said pawl from engagement with the pick wheel and thereby interrupting the take-up motion for a required number of 90 picks until the arm 13 is released by the stud 12, at which time the pawl 3 will re-engage the pick wheel and actuate the same by the usual mechanism as before. During the interruption of the take-up motion a filling 95 strip may be inserted in the usual manner. This filling strip may be for the purpose of reinforcing the fabric or it may be for ornamenting the same, as will be readily understood, the body of the fabric between the filling strips being thin and loosely beaten up.

By adjusting the stud 12 toward and away from the axis of the wheel 8 a longer or shorter engagement of the stud with the arm 100 13 may be obtained, thus shortening or lengthening the interruption to the cloth feed, as is found desirable, and making it possible to insert one or more filling strips to obtain the type of cloth desired. 105

I claim:—

1. In a take up interrupting attachment for looms, the combination with a pick wheel and an actuating pawl therefor, a rotating member, means actuated in the operation of 110 the loom for intermittently rotating said member, an arm pivoted to the loom, a stud

radially adjustable on the rotating member for displacing the arm from its normal position, and an operative connection between the arm and pawl whereby when the former is displaced the latter will be withdrawn from engagement with the pick wheel and the take up interrupted for a predetermined period.

2. In a take up interrupting attachment 10 for looms, the combination with a pick wheel and an actuating pawl therefor, a rotating member, cam actuated means operated in the operation of the loom for intermittently rotating said member, a stud radially adjustable upon said rotating member, an arm piv-

oted to the loom and lying within the path of the stud so as to be intermittently actuated thereby and a link connecting an intermediate part of the arm and an intermediate part of the pick wheel pawl whereby when the arm is depressed the pawl will be held out of operative engagement with the pick wheel for a predetermined period. 20

In testimony whereof I affix my signature in the presence of two witnesses.

GEORGE AVERY, FRANKLIN.
